UNITED STATES PATENT OFFICE.

JERROLD F. WALTON, OF STURGIS, MICHIGAN.

BED COUCH.

Application filed May 5, 1922. Serial No. 558,555.

To all whom it may concern:

Be it known that I, JERROLD F. WALTON, a citizen of the United States, residing at Sturgis, county of St. Joseph, State of Michigan, have invented certain new and useful Improvements in Bed Couches, of which the following is a specification.

This invention relates to improvements in bed couches.

10 This application is in the main a continuation of my applications for Letters Patent filed Aug. 27, 1921, Ser. No. 496,117, and filed Oct. 3, 1921, Ser. No. 505,093.

The main objects of the invention are:

15 First, to provide an improved bed couch having an extensible or adjustable section which is convenient to adjust and neat and attractive in appearance, both when adjusted as a couch and as a bed.

20 Second, to provide an improved bed couch having an adjustable section in which the adjustable section is provided with legs automatically erected or extended and locked in erected position when the adjustable section is extended and automatically collapsed when the adjustable section is telescoped onto the main frame.

Third, to provide an improved bed couch having a receptacle for the storage of bedding and the like, the couch being compact and simple in structure and the receptacle being fully accessible when the couch is extended.

Fourth, to provide in a bed couch an improved back supporting means.

Fifth, to provide in a bed couch an improved means for automatically locking the adjustable section in its collapsed position and at the same time a structure in which the adjustable section is freed by an upward and outward pull thereon.

Further objects, and objects relating to structural details, will definitely appear from the detailed description to follow.

45 I accomplish the objects of my invention by the devices and means described in the following specification. The invention is clearly defined and pointed out in the claims.

50 A structure which is a preferred embodiment of my invention is clearly illustrated in the accompanying drawing, forming a part of this application, in which:

55 Fig. I is a front perspective view of a bed couch embodying the features of my in-

vention, the adjustable section being shown in its collapsed position by full lines and in its extended position by dotted lines, the upholstery being omitted in order to better illustrate the structural details.

60 Fig. II is a fragmentary plan view with the adjustable section in its collapsed position and partially broken away, the end member of the frame being horizontally sectioned.

65 Fig. III is a fragmentary plan view of parts shown in Fig. II with the adjustable section in its extended position.

70 Fig. III^A is a detail section on a line corresponding to line 3^A—3^A of Fig. III, showing the stop means limiting the outward movement of the adjustable section.

75 Fig. IV is a detail vertical section on a line corresponding to line 4—4 of Figs. II and VII.

80 Fig. V is a fragmentary view partially in horizontal section with the back disposed in position permitting engagement and disengagement of its bottom supporting lugs with the coacting brackets.

85 Fig. VI is a detail vertical section on a line corresponding to line 6—6 of Figs. V and XI, showing details of the back supporting means.

Fig. VI^A is a side view of one of the back supporting lug plates.

90 Fig. VII is a detail vertical section on a line corresponding to line 7—7 of Fig. II, showing details of the frame structure.

Fig. VIII is a detail vertical section on a line corresponding to line 8—8 of Fig. I, showing details of the latching means for the adjustable section.

95 Fig. IX is a detail section on a line corresponding to line 9—9 of Fig. III, showing details of the legs for the adjustable section.

Fig. IX^A is a detail vertical transverse section on a line corresponding to line 9^A—9^A of Fig. II, showing the arrangement of the box adapted to receive bedding and the like.

105 Fig. X is a fragmentary view corresponding to that of Fig. II, showing a modified form of my invention in which the leg is swung to erected position by means of the spring and is collapsed against the action of such spring.

Fig. XI is a detail transverse section on a line corresponding to line 11—11 of Fig. X.

110 Fig. XII is a fragmentary view of the

modified form of my improvements shown in Figs. X and XI with the adjustable section in extended position.

In the drawing similar reference characters refer to similar parts throughout the several views and the sectional views are taken looking in the direction of the little arrows at the ends of the section lines.

Referring to the drawing, I provide a main bottom section comprising front and rear longitudinal rails 1 and 2 and cross bars 3 disposed adjacent the ends of the longitudinal rails.

I provide end members consisting of front and rear uprights 4 and 5, respectively, connected by cross bars, including the cross bars 6, disposed adjacent the lower ends thereof.

The longitudinal rails of the main bottom section are connected to the end members by dowels 7 and by the U-shaped clips 8 secured on the inner sides of the cross pieces 6 of the end members and slotted at 9 to receive the clamping bolts 10 which are engaged in slots 11 in the cross pieces 3 and provided with clamping nuts 12 so that the heads of the bolts may be engaged in the slots and the thumb nuts tightened to clamp the parts together. This provides a very secure connection for the parts and also permits of their being shipped in the knock-down and assembled by the dealer or user.

The back comprises end members 13 connected by suitable longitudinal rails. This back is detachably connected, it being provided with plates 14 mounted on the outer sides of the end pieces 13 of the back near the bottom thereof and having T-headed studs 15 adapted to engage the U-shaped brackets 16 slotted at 17 to receive the lugs when the heads are presented longitudinally thereto, that is, by swinging the back to the horizontal position as shown in Fig. V these lugs may be engaged with the slots in the coacting supporting brackets. Near the tops of the end members are U-shaped coupling members 18 substantially the same as the coupling members 8. The back end members 13 are slotted at 19 to receive the clamping bolts 20 so that when the lugs 15 are engaged and the back swung to upright position the bolts 20 may be engaged with the coupling members 18 and the parts clamped in position. By this means the back is not only effectively supported but also serves as a connecting member for the end members of the couch.

The adjustable or sliding section 21 also comprises suitable longitudinal and cross pieces and is adapted to telescope over the main section or be extended to the front thereof as indicated in the drawings. The cross pieces 3 of the main section constitute slide rails for the adjustable section. These slide rails are provided with rollers 22 at

their front ends on which the adjustable section travels. The adjustable section is also preferably provided with rollers 23 adjacent the rear edge thereof traveling on the rails 3. Guide members 24 are mounted on the adjustable section to engage one side of the rails 3,—see Fig. VII. On the other side of these rails are angle bars 25 engaged by the clips 26, so that the adjustable section is slidably supported and guided on the main section and at the same time is retained thereon. These angle bars terminate at 27 in a spaced relation from the back of the main section so that in assembling the adjustable section is positioned so that the clips 26 drop down at the rear end of the angle bars and when drawn forward pass under the same, thereby retaining the parts in sliding engagement. The angle bars 25 have stop lugs 25' struck downwardly therefrom to coact with the clips 26 when the adjustable section is in its forward position,—see Fig. IIIA.

The adjustable section is provided with legs 28 mounted on rods 29 carried by hangers 30 and 31 on the under side of the adjusting section. Each rod 29 is provided with a crank arm 32 at its rear end. Coiled springs 33 are arranged on the leg supporting rods to urge or swing the legs to their folded or collapsed position.

On the main bottom are cam rods 34 positioned so that as the adjustable section is drawn forward or extended the arms 32 ride on the cam rods positively swinging the legs 28 and supporting them in erected position against the action of their collapsing springs. When the adjustable section is moved rearwardly the springs actuate the rods to collapse the legs against the underside of the adjustable section, so that it may be collapsed over the main section.

To retain the adjustable section in its collapsed position I provide a spring locking bolt 35 which is seated in the longitudinal rail 1 of the main section to project above the same as shown in Fig. VIII. The details of this spring bolt are not illustrated as an ordinary window sash bolt or other well-known form of spring bolt will answer the purpose. The sliding section 21 is provided with a hole or keeper 36 adapted to receive the bolt when the sliding section is collapsed. A cross bar 37 is arranged on the sliding section in alignment with the bolt so that as the sliding section is drawn forward the bolt slides under this cross bar. An inclined slide 38 is provided for guiding the bolt into its keeper as the sliding section is moved to its rear position.

When it is desired to release or disengage the sliding section from the bolt it is done by an upward and forward pull on the sliding section. This simple locking bolt retains the sliding section in its collapsed position.

tion and at the same time it is automatically engaged and is easily disengaged by the movement which would naturally be made in pulling out the sliding section.

- 5 I provide the main section with vertically disposed cross pieces 39 arranged at the inside of the slide rails and leg actuating mechanism described. A bottom 40 extends between these cross pieces to the rear longitudinal rail providing a receptacle 41 for the reception of bedding and the like. This receptacle is provided with a cover 42 hinged at 43. The front of the receptacle is thus spaced from the front of the frame so 10 that the legs can collapse into the space shown in Fig. IX^A and the cover may be opened when the adjustable section is collapsed.

With the parts thus arranged I provide a substantial storage space and this without 20 increasing the dimensions of the parts.

In the modification shown in Figs. X, XI and XII the springs 44 are arranged to swing the legs 28 to erected position when 25 the sliding section is drawn forward, the cam rod 45 being arranged to collapse the legs against the action of the spring. While this embodiment is very satisfactory that shown as the preferred construction has the 30 advantage of positively locking the legs in their erected position when the sliding section is extended.

I have illustrated and described my improvements in embodiments which I have 35 found very practical. I have not attempted to illustrate or describe certain other modifications or adaptations which I contemplate as I believe the disclosure made will enable those skilled in the art to which my invention relates to embody or adapt the same as 40 may be desired.

Having thus described my invention, what I claim as new and desire to secure by Letters Patent, is:

45 1. In a couch bed, the combination of a main section, an adjustable section slidably mounted on said main section to telescope therewith, a leg for said adjustable section, a leg supporting rod pivotally mounted on 50 said adjustable section transversely thereof and having a crank arm, a spring acting to hold said leg normally collapsed, and a cam member on said main section coacting with the arm of said leg supporting rod, whereby 55 the leg is erected when the adjustable section is moved to its extended position.

2. In a couch bed, the combination of a main section, an adjustable section slidably mounted on said main section to telescope 60 therewith, a leg for said adjustable section, a leg support pivotally mounted on said adjustable section and having a crank arm, and a cam member on said main section coacting with said arm on said leg support 65 whereby the leg is erected and retained in

erected position when the adjustable section is moved to its extended position.

3. In a bed couch, the combination of a main bed bottom section and an adjustable bed bottom section slidably mounted on said main section to telescope therewith or to be extended by horizontal sliding movement to the side thereof, a leg support pivotally mounted on said adjustable section, a leg for said adjustable section mounted on said leg support, and a cam member on said main section operatively associated with said leg support whereby when the adjustable section is slidably adjusted to its extended position the leg is erected and held 70 in erected position by said cam.

4. In a bed couch, the combination of a main bed bottom section and an adjustable bed bottom section slidably mounted on said main section to telescope therewith or to be extended by horizontal sliding movement to the side thereof, a leg support pivotally mounted on said adjustable section, a leg for said adjustable section mounted on said leg support, and a cam member on said main section operatively associated with said leg support whereby the leg is actuated 80 to and supported in one position by the sliding adjustment of said adjustable section.

5. In a bed couch, the combination of a main bed bottom section and an adjustable bed bottom section slidably mounted on said main section to telescope therewith or to be extended by horizontal sliding movement to the side thereof, a leg collapsibly mounted on said adjustable section, a spring for holding said leg in one position, and means for positively actuating said leg against the tension of said spring and supporting it in 100 actuated position on the sliding movement of the adjustable section in one direction comprising a cam member on said main section, and a member connected to said leg and having sliding engagement with said cam member whereby the leg is actuated by the sliding movement of said adjustable section.

6. In a couch bed, the combination of a main section comprising a frame having a bottom for a portion thereof providing a receptacle for bedding, the front and ends of said receptacle being spaced from the front and ends of the frame, a cover for said receptacle hinged at one longitudinal 115 edge, an adjustable section comprising a frame slidably mounted on said main section frame to telescope over the same, the rear frame member of said adjustable section frame lying at the front of said cover 120 when the adjustable section is extended so that the cover may then be opened, legs pivotally mounted on said adjustable section to collapse against the underside thereof, the legs when collapsed lying in front 125 130

of said receptacle, and means for collapsing said legs disposed in the spaces at the ends of the receptacle.

7. In a couch bed, the combination of a main section comprising a frame having a bottom for a portion thereof providing a receptacle for bedding, the front and ends of said receptacle being spaced from the front and ends of the frame, an adjustable section comprising a frame slidably mounted on said main section frame to telescope over the same, legs pivotally mounted on said adjustable section to collapse against the underside thereof, the legs when collapsed lying in front of said receptacle, and means for collapsing said legs disposed in the spaces at the ends of the receptacle.

8. In a couch bed, the combination of a main section having a bottom for a portion thereof providing a receptacle adapted to receive bedding or the like, an adjustable section comprising a frame slidably mounted on said main section to telescope over the receptacle, legs pivotally mounted on said adjustable section to collapse against the underside thereof at the outer side of the planes of the vertical walls of said receptacle, and means for collapsing said legs disposed at the outer side of such planes.

9. In a couch bed, the combination of a main section having a bottom for a portion thereof providing a receptacle adapted to receive bedding or the like, an adjustable section comprising a frame slidably mounted on said main section to telescope over the

receptacle, and legs mounted on said adjustable section to collapse against the underside thereof at the outer side of the vertical walls of said receptacle.

10. In a couch bed, the combination of a main section, an adjustable section, slidably mounted on said main section to telescope over the same when collapsed, a slide rail on said main section, a supporting roller for said adjustable section disposed at the front end of said slide rail, a roller disposed on said adjustable section to travel on said rail, a guide on said adjustable section coacting with one side of said slide rail, an angle bar secured on the other side of said slide rail and with its end spaced from the back and a retaining clip on said adjustable section adapted to engage the under side of said angle bar, said clip being disengaged with said bar by movement to the rear thereof.

11. In a couch bed, the combination of a main section, an adjustable section, slidably mounted on said main section to telescope over the same when collapsed, a slide rail on said main section, a guide on said adjustable section coacting with one side of said slide rail, an angle bar secured on the other side of said slide rail and with its end spaced from the back and a retaining clip on said adjustable section adapted to engage the under side of said angle bar.

In witness whereof, I have hereunto set my hand and seal.

JERROLD F. WALTON. [L.S.]
